UNITED STATES PATENT OFFICE.

FERDINAND M. HAMMER, OF BUFFALO, NEW YORK.

MILK-BOTTLE CAP.

Application filed December 21, 1921. Serial No. 523,864.

To all whom it may concern:

Be it known that I, FERDINAND M. HAMMER, a citizen of the United States, residing at Buffalo, in the county of Erie and 5 State of New York, have invented certain new and useful Improvements in Milk-Bottle Caps, of which the following is a specification.

My invention relates to caps or closures 10 for milk bottles, jars and other vessels, and more particularly to that type of cap for closing milk bottles adapted to be used temporarily while the bottle is filled or partly filled and to be thrown away after 15 the bottle is emptied.

Caps or closures of this kind are invariably constructed of card board, or similar material, of a thickness that would prevent the ready flexing or bending of the same, 20 particularly on a straight line; and in caps used for this purpose in which provision is made for swinging a portion thereof to permit of pouring out the contents of the bottle, the cap or closure is necessarily made 25 of comparatively thin material, in consequence of which its durability is impaired and the gripping qualities at the edge greatly lessened, with the result that thin caps of this kind are found to be unsatisfactory for the purpose intended and do not 30 properly seal the bottle. Moreover, when using caps of this kind, the contents of the bottle becomes soured more easily and is subject to contamination which, if it does 35 not spoil the contents, will at least effect the taste of the same.

The object of my invention is the provision of a cap or closure of this type which can be constructed of a single thickness of 40 comparatively thick card board or other similar material and yet enable one portion thereof to be swung outwardly with reference to the other so as to provide a pouring orifice while retaining a portion 45 of the cap or closure against its seat provided in the neck of the bottle.

A further object is to so construct the cap or closure that the marginal portion thereof on its inner or under side remains flush or 50 unbroken and may be tightly seated against the cap-seat formed in the neck of the bottle.

With these and other objects in view the invention consists in the novel features of 55 construction and in the arrangement and combination of parts to be hereinafter de-

scribed and more particularly pointed out in the subjoined claims.

In the drawings,—

Fig. 1 is a perspective view of a milk 60 bottle furnished with my improved cap or closure.

Fig. 2 is a perspective view of the same showing the bottle in pouring position with one part of the cap or closure swung outwardly to create a pouring orifice. 65

Fig. 3 is a plan view of my improved cap or closure.

Fig. 4 is an inverted view of the same.

Fig. 5 is a vertical section through the 70 upper end of a bottle having my improved cap or closure fitted thereto, this cap or closure being shown in full sealing position.

Fig. 6 is a similar view showing one portion of the cap swung outwardly while the 75 other portion is retained in seated position against the seat provided for the cap.

Fig. 7 is a perspective view of the cap viewed from the inner or under side thereof.

Fig. 8 is a vertical section through the 80 upper end of the bottle taken on line *a—a*, Fig. 5.

Reference being had to the drawings in detail, like numerals refer to like parts in the several figures.

The reference numeral 9 designates a bottle which is provided with a cap or closure-seat 10 at its upper end, this seat being formed by enlarging the internal diameter of the bottle neck at its extreme 90 outer end, as is commonly provided for in milk bottles.

11 designates my improved cap or closure which is constructed of a single thickness of card board, or any other suitable material 95 having a certain degree of flexibility but being sufficiently thick to give the necessary firmness and durability required of a cap of this kind in order to withstand the usage to which it is subjected and retain its position against the seat provided therefor.

The thickness of the cap is such that it will not flex along a straight line diametrically or parallel to a diametrical line passing through the cap, such thickness being required to assure the proper binding or impinging effect of the cap at its edge against the surrounding wall rising from the cap seat. This cap is of circular formation and is provided at its edge with a lip or handle 110 12. When the cap is forced into the upper open end of a bottle, this lip is bent up-

wardly or substantially at right angles to the face of the cap, as shown in Fig. 1; this being possible due to the fact that the lip is comparatively narrow and the bend is 5 not made along an extended line.

The cap as thus far described does not differ from the regulation cap now in use, but in such caps no provision is made for bending one portion of the cap at an angle 10 to another so as to form a pouring orifice without displacing the cap as a whole, except that the cap is weakened by scoring or reducing the thickness of the material along a straight line from one point of the 15 edge of the cap to an opposite point, or by providing grooves which are extended circularly around the marginal portion of the cap in order to provide a proper seating face for the same against the cap seat 20 formed in the neck of the bottle.

My improved cap is formed by providing a diametral groove or depression 13, or a straight-lined groove or depression parallel with a plane passing diametrically through 25 the cap, said groove or depression being substantially of V-shape in cross section, as shown in Fig. 5, and terminating in pointed ends, as at 14, near the edge of the cap. By thus terminating the groove or depression 30 short of the edge of the cap, a smooth portion 15 is retained between each end of the groove or depression 13 and the edge of the cap, thus forming a cap with the marginal portion unbroken or smooth-faced throughout 35 out so that the cap may be seated securely against the seat of the bottle to completely seal the contents of the latter. This straight-lined groove 13 may be formed or pressed into the cap while the latter is in moist condition, either during or after the making of 40 the card board or other material from which the cap is formed; but as caps of this kind are invariably impregnated with paraffin, the straight-lined groove may be formed in 45 the cap while moistened under this treatment, or it may be formed at any other time whether or not the same is moistened, as this depends considerably on the material used. It is of course possible to form a groove of 50 this kind within the cap when the same is in a dry condition, when using certain kinds of material, but owing to the custom of supplying new caps to the bottle each time the same is filled, the bottler will invariably select a 55 cheaper grade of material which would not enable the groove to be formed in as clearly defined a manner when dry as when the cap is moistened, but as this invention does not pertain to the method of constructing the 60 cap I do not wish to confine myself to any particular method, as it is quite apparent that this groove may be formed in various ways.

It is to be noted that the groove is formed 65 in the cap from the outer face, which results

in a diametral rib or elevation 18 being formed on the inner or under face thereof, and if this elevation were continued to the edge of the cap the latter could not be properly seated against the cap seat of the bottle, 70 As clearly shown in Figs. 3, 4 and 7, two comparatively short smooth-face portions are provided at opposite ends of the groove, and as these portions are only a trifle wider than the width of the cap seat in the bottle, the 75 cap may be easily bent at these points.

The groove 13 divides the cap into two parts 16, 17, and with the cap made of comparatively thick material it may be forcibly pressed into the mouth of the bottle without 80 causing the same to bend or flex at opposite ends of the groove. When the caps are thus forced into the bottle the lip or handle 12 extends upwardly and may be readily gripped for swinging one part of the bottle with 85 respect to the other, as clearly shown in Fig. 2. This provides a pouring orifice 19 without removing the cap as a whole from its seat, and when the desired quantity of the contents of the bottle is poured out, the 90 swing portion 16 may be swung back against the cap-seat, again assuming the position shown in Fig. 1 and fully sealing the bottle.

By providing the V-shaped groove, an integral hinge is formed on the cap, and by 95 terminating such groove short of the edge of the cap at two points, the unbroken or smooth-faced portions at opposite ends of the groove will, due to their short lengths, permit of swinging or bending the portion 10 16 at these points on a straight line with the center of the groove 13. When the swinging portion 16 is returned to normal or closing position, the sealing effect of the two portions at opposite ends of the groove is not disturbed. It is of course not necessary that the 10 11 groove be of V-formation in cross section, since it may be otherwise formed without departing from my invention or sacrificing any of the advantages thereof.

Having thus described my invention, what I claim is,—

1. A removable bottle cap formed of a single thickness of material and having a groove terminating at opposite ends short of the edge of the cap at two points to permit one portion of the cap to be swung with reference to the other.

2. A removable disk-like cap for bottles and the like formed of a single thickness of 12 material and adapted to be fitted into the mouth thereof and provided with a groove terminating at opposite ends short of the edge of the cap at two points so that one portion of the cap may be swung with respect to 12 the other to open or close the mouth of the bottle without displacing the cap from the bottle.

3. A cap for milk bottles and the like comprising a disk formed of a single thickness 13

- of material and having a groove terminating short of the edge of the cap at two points so as to provide an unbroken surface around the entire marginal portion of the cap.
- 5 4. A cap for milk bottles and the like, comprising a disk-like body formed of a single thickness of material and having a groove pressed thereinto from its outer face and terminating short of the edge of the cap at two
- 10 10 points so as to provide two smooth portions between such points and the ends of said groove.

5. A cap for milk bottles and the like comprising a flat body portion having a V-shaped groove terminating short of the edge of the cap at two points.

6. A cap for milk bottles and the like consisting of a somewhat flexible disk-like body portion having a groove pressed thereinto from its upper surface which terminates short of the edge of the cap at two points,

said cap having otherwise a smooth upper and a smooth under surface.

7. A cap formed of a single thickness of material adapted to be inserted into the neck 25 of a bottle and be held therein by frictional contact of its edges therewith, said cap being provided with a groove having opposite ends terminating short of the edge at two points thereof to enable one portion of the 30 cap to be swung relative to the other, said first-mentioned portion being provided with a lip or handle.

8. A milk bottle cap formed of a thin sheet of material provided with a groove extending diametrically but terminating short 35 of the edge of the cap at diametrically opposite points so as to provide a smooth marginal portion at the underside of the cap.

In testimony whereof I affix my signature. 40

FERDINAND M. HAMMER.
